The ornamental design for an arch-triangle curling iron, as shown and described.

DESCRIPTION

FIG. 1 is a side view of the arch-triangle curling iron the side opposite being a mirror image thereof;

FIG. 2 is a top view of the arch-triangle curling iron;

FIG. 3 is a front view of the arch-triangle curling iron; and,

FIG. 4 is a rear view of the arch-triangle curling iron.

The surfaces or portions of the article not shown in the drawing or described in the specification forms no part of the claimed design.
